To all whom it may concern:

Be it known that I, Hans Boepple, a citizen of the United States of America, residing in New York city, county of New York, and State of New York, have invented a new, original, and ornamental Design for a Sweater, of which the following is a specification, reference being had to the accompanying drawing, forming part thereof, wherein,

The rear of the sweater is substantially the same in appearance as the front shown, except for the button closure at the central neck portion.
